Primary Examiner — Brett Miller*Assistant Examiner* — Jessica M Gebhart(74) *Attorney, Agent, or Firm* — Rick B. Yeager(57) **CLAIM**

The ornamental design for a butterfly cell phone clutch purse, as shown and described.

DESCRIPTION

FIG. 1 is a top view of the outside of a butterfly cell phone clutch purse in a fully-open orientation.

FIG. 2 is a top view of the butterfly cell phone clutch purse of FIG. 1 in a fully-closed orientation.

FIG. 3 is a bottom view of the butterfly cell phone clutch purse of FIG. 1 in a fully-open orientation in a first internal configuration with a cell phone pocket.

FIG. 4 is a side view of the butterfly cell phone clutch purse of FIG. 3 in a partially-open orientation; and,

FIG. 5 is a bottom view of the butterfly cell phone clutch purse of FIG. 1 in a fully-open orientation in a second internal configuration without a cell phone pocket.

The evenly spaced dashed broken lines in the figures depict stitching and are part of the claimed design, The dash-dot-dash broken lines used in FIGS. 3 and 4 depict environmental subject matter that form no part of the claimed design.

1 Claim, 5 Drawing Sheets(56)
